TOGGLE ACTUATED HAND CLAMP WITH RELEASE TRIGGER Leland F. Blatt, Grosse Pointe Woods, and
Arthur E. Sherman, Detroit, Mich.

Application January 26, 1955, Serial No. 484,114

2 Claims. (Cl. 144—302)

This invention relates to a portable hand clamp, and more particularly to a trigger release mechanism in conjunction with the hand clamp.

Heretofore, in hand clamp constructions of this type, upon a clamping action of a clamp, the two jaws are brought into compressive and tight engagement with an object to be clamped. In order to release the said clamp it has been necessary to use both hands to manually pry apart the said handles.

It is the object of the present invention to provide a trigger release mechanism whereby the clamp may be released with one hand by so actuating the said trigger as to effect an initial spreading apart of the said handles.

It is the further object of the present invention to provide a trigger release device between the said handles which is pivotally mounted between the said handles and supported at the pivotal connection between the handles and with the trigger mechanism having an operating cam adapted to apply a camming pressure to one of the said handles for effecting an initial separation thereof and a release of the clamp jaws.

These and other objects will be seen from the following specification and claims in conjunction with the appended drawing, in which:

Fig. 1 is a side elevational view of the present portable hand clamp.

Fig. 2 is a section taken on line 2—2 of Fig. 1; and Fig. 3 is a plan view of the clamp shown in Fig. 1.

It will be understood that the above drawing illustrates merely a preferred embodiment of the invention and that other embodiments are contemplated within the scope of the claims hereafter set forth.

Referring to the drawings, Figs. 1 and 3, the present portable hand clamp comprises a pair of opposed elongated jaws 11 and 12 of substantially symmetrical form. Jaw 11 terminates at one end in the upright boss 13 which is transversely apertured throughout its height and interiorly threaded as at 17. Said boss is normally spaced from and in substantial alignment with a second boss 14 at the corresponding one end of jaw 12, boss 14 having a flat inner surface 16 defining a supporting anvil.

The upright spindle 18 in the nature of a threaded bolt is threadedly projected through boss 13 in the desired position of adjustment and secured in such position of adjustment by the lock nut 20. The head 19 of said bolt is adapted to operatively engage the object which is to be clamped in cooperation with anvil 16. The said jaws 11 and 12 are formed with transverse webbing 15 for reinforcing the same.

The bosses 13 and 14 of the said jaws are defined herein as being at one of the ends of the said elongated jaws 11 and 12. The other ends of the said jaws are arranged in overlapping registry and are transversely apertured to receive the interconnecting rivet 25 which serves as the pivotal connection between the said jaws. The ends of the said jaws 11 and 12 corresponding to this pivotal

connection include the curved portions 21 at the rear of the said jaws, which portions terminate in the central overlapping plate formations 22, through which the said rivet 25 cooperatively extends. The central overlapping plate formations 22 of each of the said jaws terminate in the wall portions 24 which define the inner opposed edge portions of the said jaws 11 and 12.

Each of the said jaws 11 and 12 at their one ends adjacent the formed portions 21 have transverse apertures 26 in substantial vertical alignment whereby each of the said jaws may be pivotally connected with its corresponding operating handles 27 and 28, respectively, as by the rivets 33 and 34.

The formation of each of the handles is the same, said handles being symmetrical and in opposed relation. Said handles include the forwardly arranged curved portion 29 defining the ends of said handles adjacent the pivots 33 and 34 therefor. Said ends 29 are arranged in overlapping registry and are curved as at 30 around the central overlapping portions of the said handles, which portions are transversely apertured to receive the rivet 35 by which the handles 27 and 28 are pivotally interconnected.

The curved portions 30 of each of the said handles terminate in the opposed outwardly diverging cam surfaces 31, which in turn, blend with the inner wall portions 32 of the opposing handles 27 and 28.

Thus, as shown in Fig. 1, jaw 11 is rearwardly of the overlapping jaw 12 at their pivotal connection 25. The front end portion of handle 27 as it is pivotally mounted upon jaw 11 is arranged forwardly of said jaw and at the same time overlaps the front end portion of handle 28, which front end portion of said latter handle 28 is positioned under the overlapping rear portion of jaw 12 to thereby complete the clamp construction.

The pivotal connection between the said jaws themselves as at 25, the pivotal connection between the handles and the respective jaws as at 33 and 34, and the pivotal connection between the two handles as at 35 are substantially conventional constructions.

The important part of the present invention pertains to the release of manually operable trigger 38 which is arranged between the two handles 27 and 28 and can be actuated by the same hand which grasps both of the said handles for effecting a release of the clamp and its jaws from a clamped position.

For this purpose there are provided upon opposite sides of the said handles a pair of parallel spaced elongated trigger mounting plates 36. Said plates are pivotally mounted at their forward ends to the pivotal connection 35 between handles 27 and 28 as by the rivet 35.

Transversely arranged pin 37 interconnects the opposite ends of plates 36 and is positioned between handles 27 and 28. Trigger 38 intermediate its ends and towards its forward end is pivotally mounted upon the said pin 37 between plates 36.

The forward portion of trigger 38 as at 39 is in the nature of a converging cam element which is positioned between the forward portions 31 or cam surfaces of the said handles and is adapted to operatively engage either of the said cam surfaces for initially prying apart the handles 27 and 28 from a clamping position.

In this connection the pin 37 supported by plates 36 will be fulcrumed upon and against one of the cam surfaces 31, and the cam element 39 forming a part of said trigger will operatively engage the cam surface of the other handle to thereby forcefully pry or spread apart handles 27 and 28 to thereby effect a release of the jaws 11 and 12.

The specific mounting of trigger 38 on pin 37 between the free ends of mounting plates 36 has several important advantages. In the first place this arrangement of the

trigger provides for a mounting of the trigger as well as the opposite ends of plates 36 upon the same pivot 35 which interconnects the handles 27 and 28. Inasmuch as the inner surface of both handles are provided with cam surfaces 31, and due to the specific location of the cam 39, the trigger may be operated in either direction for effecting a release of the clamp. In this construction the free ends of plates 36 are interconnected by a central pivot pin 37, which may be alternately fulcrumed against either handle 27 or 28. Accordingly the cam 39 will operatively engage the cam surface 31 on the other handle.

The advantage resides in the fact that regardless of the position of the hand clamp, the squeezing of one handle and the trigger towards the same, effects a release. If the trigger were operable only in one direction and if the clamp were upside down, the squeezing of the trigger would not effect a release. The present specific mounting for the trigger thus assures that the clamp will be released regardless of its position.

The present construction also centrally positions the trigger between both handles, so that it is not mounted merely upon one and accordingly provides for a symmetrical construction with particular ease of assembly.

Having described our invention, reference should now be had to the claims which follow for determining the scope thereof.

We claim:

1. A portable clamp comprising a pair of opposed elongated jaws pivotally connected at their one ends, a pair of opposed handles pivotally interconnected at their one ends and each handle, respectively, pivoted at said one ends to one of said jaws at their one ends, and an elongated trigger interposed between said handles and pivotally connected intermediate its ends to and adjacent the said one ends of said handles, said trigger having a short cam arm at its free end arranged between said

handles adjacent their one ends and adapted for selective operative engagement therewith for releasing said handles and jaws from a clamped position, the pivotal mounting of said trigger including a pair of parallel spaced elongated plates upon opposite sides of said handles pivotally joined at their one ends to the pivotal connection between said handles and pivotally joined at their other ends to said trigger intermediate its ends.

2. A portable clamp comprising a pair of opposed elongated jaws pivotally connected at their one ends, a pair of opposed handles pivotally interconnected at their one ends and each handle, respectively, pivoted at said one ends to one of said jaws at their one ends, and an elongated trigger interposed between said handles and pivotally connected intermediate its ends to and adjacent the said one ends of said handles, said trigger having a short cam arm at its free end arranged between said handles adjacent their one ends and adapted for selective operative engagement therewith for releasing said handles and jaws from a clamped position, the pivotal mounting of said trigger including a pair of parallel spaced elongated plates upon opposite sides of said handles pivotally joined at their one ends to the pivotal connection between said handles, a pin interconnecting the other ends of said plates positionable transversely of and between said handles and adapted for fulcruming engagement with one of said handles, said trigger being pivotally mounted upon said pin.
